(57) **CLAIM**

The ornamental design for an radiant heater, as shown and described.

DESCRIPTION

FIG. 1 is an isometric view of a first embodiment of the radiant heater according to the invention, showing the front face as curved and having a face mesh with oval holes; FIG. 2 is a front face view of the radiant heater of FIG. 1; FIG. 3 is a back elevation view of the radiant heater of FIG. 1; FIG. 4 is a top view of the radiant heater of FIG. 1; FIG. 5 is a bottom view of the radiant heater of FIG. 1; FIG. 6 is a right end view of the radiant heater in FIG. 1, the left end view being a mirror image thereof; FIG. 7 is a second embodiment of the radiant heater in which the front face view is similar to that of FIG. 2, but the front face having round holes, and all other views being the same; FIG. 8 is a third embodiment of the radiant heater in which the front face view is similar to that of FIG. 2, but the front face having hexagonal holes, and all other views being the same; FIG. 9 is a fourth embodiment of the radiant heater in which the front face view is similar to that of FIG. 2, but the front face having square holes, and all other views being the same; FIG. 10 is an isometric view of a fifth embodiment of the radiant heater according to the invention, showing the front face as flat and having a face mesh with oval holes.

FIG. 11 is a front face view of the radiant heater of FIG. 10; FIG. 12 is a back elevation view of the radiant heater of FIG. 10;

FIG. 13 is a top view of the radiant heater of FIG. 10; FIG. 14 is a bottom view of the radiant heater of FIG. 10; FIG. 15 is a right end view of the radiant heater in FIG. 10, the left end view being a mirror image thereof;

FIG. 16 is a sixth embodiment of the radiant heater in which the front face view is similar to that of FIG. 10, but the front face having round holes, and all other views being the same; FIG. 17 is a seventh embodiment of the radiant heater in which the front face view is similar to that of FIG. 10, but the front face having hexagonal holes, and all other views being the same; and,

FIG. 18 is a eighth embodiment of the radiant heater in which the front face view is similar to that of FIG. 10, but the front face having square holes, and all other views being the same.
